UNITED STATES PATENT OFFICE.

WILLIAM CHARLES DOWD, OF QUINCY, ILLINOIS.

CENTRIFUGAL PUMP.

Application filed September 13, 1922. Serial No. 587,938.

To all whom it may concern:

Be it known that I, WILLIAM CHARLES DOWD, a citizen of the United States, and a resident of Quincy, in the county of Adams and State of Illinois, have invented a new and useful Improvement in Centrifugal Pumps, of which the following is a full, clear, and exact description.

My invention relates to centrifugal pumps, and it consists in the combinations, constructions and arrangements herein described and claimed.

One difficulty in the use of centrifugal pumps lies in the fact that a centrifugal pump is ordinarily built for large capacities and requires large capacities to operate efficiently. With the ordinary pump, as the head decreases, the horse power required to drive the pump increases, due to the fact that the pump is pumping more water in a given time, i. e., is operating under greater capacity. Many times it is highly desirable to have a pump which will operate on substantially the same horse power under varying heads.

The main object of this invention is to provide a centrifugal pump having a comparatively flat characteristic, or one which requires substantially the same amount of power to drive it at varying heads.

A further object of my invention is to provide a simple means for changing the ordinary centrifugal pump into one having a flat or nearly constant horse power characteristic, for any delivery of capacity and head.

Other objects and advantages will appear in the following specification, and the novel features of the invention will be particularly pointed out in the appended claim.

My invention is illustrated in the accompanying drawings, forming part of this application, in which—

Figure 1 is a central longitudinal section through a portion of the device,

Figure 2 is a transverse central section through the impeller,

Figure 3 is a section of a ring,

Figure 4 is an end view of the device, and

Figure 5 is a side elevation, a portion being shown in section.

Referring now to Figures 4 and 5, I have shown therein a centrifugal pump comprising a base 1, upon which is mounted a casing 2 having an inlet 3 and an outlet 4.

The inlet communicates with an interior chamber 5, which communicates in turn with the vanes of an impeller 7. The latter is of the usual type, being curved as shown in Figure 2 to provide curved passages 8 which enlarge as they near the outer edge of the impeller. As will be seen from Figure 1, the passages 8 lead from each side of the casing to a common passage 9 at the center. Ordinarily, the water which is forced through the passages 8 and 9 between the vanes is thrown into an outer annular chamber 10 which leads to the discharge pipe 4.

In the present instance, however, I provide a ring such as that best shown in Figures 2 and 3. This ring has a body portion 11 which is shrunk onto the rim of the impeller. The body portion of the ring 11 has recesses 12 which register with the openings between the vanes 6, the wall of the recesses being curved as shown in the drawings. At 13 are outlets for the entrance of the water into the annular chamber 10. It will be noted that one wall of the outlet or opening 13 forms a substantial continuation of one wall of the vane 6.

From the foregoing description of the construction of the device, the operation thereof may be readily understood. In the ordinary centrifugal pump the ring 11 is omitted, and the water has free movement into the chamber 10. I have found that by

providing the ring 11 and curving the walls thereof in the manner shown, the water, which would ordinarily be thrown out from between the vanes 6, is directed toward the small openings 13, the result being that the flow of water is throttled and is ejected into the chamber 10 at a very high speed, which does not vary materially with considerable variation in the head. With a pump of this kind, it is possible to pump the water or other liquids with a substantially constant application of power. Electric motors which are used to drive pumps constructed according to the present invention therefore are not liable to be overloaded, as is the case with pumps in which the horse power characteristic rises speedily as the head varies.

I claim:

A centrifugal pump comprising a casing having an inlet and an outlet, an impeller having curved vanes spaced apart to pro-

vide curved fluid passages enlarging toward the outer rim of the impeller, and means carried by the impeller for throttling the fluid delivered from said curved passages, said means comprising a ring secured to the rim of the impeller, said ring having a recess registering with the end of the curved passage between spaced apart

vanes, and being provided with an opening contiguous to one wall of the adjacent vane, the wall of said recess being curved from the edge of the wall of a vane in advance to the opening in the succeeding vane, whereby the fluid is directed toward the opening.

WILLIAM CHARLES DOWD.
